UNITED STATES PATENT OFFICE

2,468,820

MEANS FOR COOLING PROJECTED DEVICES

Robert H. Goddard, deceased, late of Annapolis, Md., by Esther C. Goddard, executrix, Worcester, Mass., assignor of one-half to The Daniel and Florence Guggenheim Foundation, New York, N. Y., a corporation of New York

Application February 1, 1947, Serial No. 725,805

2 Claims. (Cl. 102—92.5)

1

This invention relates to the cooling of devices such as rockets, rocket craft and projectiles which are caused to travel through the atmosphere at very high rates of speed. It is found that the speeds now used for such devices cause an extreme rise in temperature due to friction. The temperatures thus produced may even be above the melting point of any available metal or other material which is suitable for use in the outer casings of such projected devices.

It is the general object of the present invention to provide means for effectively cooling the outer surface of a projected device, even when traveling at excessive speed.

To the accomplishment of this general object, improved constructions have been developed by which water or other suitable liquid coolant may be supplied to the outer surface of the projected device in such manner that it will form a protecting film which is continuously replenished.

The invention further relates to arrangements and combinations of parts which will be hereinafter described and more particularly pointed out in the appended claims.

Preferred forms of the invention are shown in the drawings, in which

Fig. 1 is a partial sectional elevation of the front portion of a projected device;

Fig. 2 is an enlarged detail section of the extreme front end of said device;

Fig. 3 is a view similar to Fig. 2 but showing a modified construction;

Fig. 4 is a fragmentary sectional view of a portion of the side wall of the projected device and showing a further modification;

Figs. 5 and 6 are fragmentary perspective views, partly in section and showing additional modified side wall spray constructions;

Fig. 7 is an enlarged sectional detail of certain parts shown in Fig. 6;

Fig. 8 is a sectional elevation of the front end of a projected device and showing an additional modified spraying construction; and

Fig. 9 is an enlarged sectional detail of a further modification of the construction shown in Fig. 8.

Referring to Figs. 1 and 2, a portion of a projected device D is shown in section, with a front end member 10 and with a side casing 11. A feed pipe 12 extends axially toward the front end of the device D and receives water or some other liquid coolant under pressure from any suitable supply.

A tube 20 extends from the pipe 12 to an axial opening 21 at the nose of the end member 10.

2

Liquid ejected through the tube 20 and opening 21 spreads over the outer surface of the end portion 10 and forms a protective film therefor.

Branch pipes 24, 25, 26 and 27 connect the feed pipe 12 to an annular series of rearwardly-directed outlets 30, through which jets of water may be sprayed over the outer surface of the casing 11 in the front and middle portions of the device D.

10 The entire front surface of the projected device is thus provided with a protecting film of water or other liquid coolant, which is continuously renewed and which effectively prevents excessive rise in temperature.

15 In the construction shown in Fig. 3, the opening 32 at the front of the projected device D' is provided with an axial spreader 33 which directs the coolant rearward over the end portion of the casing and which also protects the open front end 20 of the axial tube 34 from excessive direct atmospheric pressure at high speed.

In the construction shown in Fig. 4, branch pipes 36 corresponding to the pipes 24 to 27 previously described connect direct with rearwardly 25 tangential spray openings 38, this construction being somewhat simpler than that shown in Fig. 1.

20 In the construction shown in Fig. 5, one or more branch pipes 40 connect with an annular casing 30 41 which encloses a distributing recess 42. The casing 44 of the projected device D2 has an annular slot 45 through which the liquid coolant is distributed rearward over the outer surface of the casing 44.

25 In the construction shown in Fig. 6, one or more branch pipes 50 connect into an annular casing 51 providing a recess 52 to receive the liquid coolant and from which recess the coolant is sprayed through tangential openings 53 (Fig. 7). The outer surface of the device D3 is thus effectively cooled.

30 In Fig. 8, the projected device, such as a projectile D4, is provided with a front end portion or nose 60 formed of porous material. An inner casing member 61 encloses a chamber 62 to which liquid coolant under pressure is supplied through a pipe 63. As the coolant is maintained under pressure, it makes its way outward through the porous material of the nose 60 and forms a film 50 on the outer surface, as in the constructions previously described.

35 A slight modification of this latter construction is shown in Fig. 9, in which the porous material 60a is provided in its outer surface with tangential recesses 70 which are directed rearwardly and

which assist in quickly forming a protective film.

With all forms of the invention, effective cooling by a protecting outer film is attained by very simple and effective constructions.

Having been thus described, the invention is not to be limited to the details herein disclosed, otherwise than as set forth in the claims, but what is claimed is:

1. In a projected device having an enclosing casing, means for cooling said casing comprising a porous wall forming the nose portion of said casing, and means to supply a liquid coolant under pressure to the inner face of said porous wall and to force said coolant through said wall to form a protective film on the outer face thereof and on 10 said casing.

2. The combination in a projected device as set 15

forth in claim 1, in which the outer face of said porous wall is provided with a plurality of rearwardly tangential recesses from which the coolant is sprayed over said wall and casing.

ESTHER C. GODDARD,
*Executrix of the Last Will and Testament of
Robert H. Goddard, Deceased.*
